METHOD OF MAKING NOSE GUARDS

James Wilson Welsh, Providence, R. I., assignor to The Welsh Manufacturing Company, Providence, R. I., a corporation of Rhode Island

Application December 29, 1933, Serial No. 704,393

3 Claims. (Cl. 18—59)

The present invention relates to methods of making nose guards for ophthalmic mountings, particularly nose guards comprising non-metal material.

In Letters Patent of the United States, No. 1,955,843 granted April 24, 1934, there is disclosed a new and improved nose guard comprising an unbacked, non-metal, nose rest that has essentially the flexibility, softness and other characteristics of the non-metal material, but that is nevertheless reinforced by a metal support to compensate for the weakness of such non-metal material.

An object of the present invention is to provide a new and improved method of making a guard of the character disclosed in the said Letters Patent.

According to the construction disclosed in the said Letters Patent, the metal support extends entirely, or substantially, through the non-metal nose rest, from the rear face to, or near to, the front face. This introduces the actuality, or, at least, the possibility, of the metal coming into contact with the skin of the wearer's nose, and another object of the invention is to provide a novel method of making a guard of the above-described character that shall eliminate this defect.

In the guard of the said Letters Patent, furthermore, the metal and the non-metal parts are secured together in such way that they sometimes have a tendency to become separated from each other, and still a further object of the invention, therefore, is to provide a new and improved method of making a guard of the above-described character the metal and the non-metal parts of which shall be joined together so securely as to be almost inseparable.

Another object is to provide a new and improved method of making nose guards of the said character.

Other and further objects will be explained hereinafter and will be particularly pointed out in the appended claims.

The invention will now be explained in connection with the accompanying drawings, in which Fig. 1 is a rear elevation of an ophthalmic mounting embodying a nose guard made in accordance with the present invention; Fig. 2 is a plan of the same; Figs. 3 and 4 are enlarged sections taken upon the lines 3—3 and 4—4 of Fig. 1, looking in the directions of the arrows; Fig. 5 is a rear elevation of the novel guard manufactured in accordance with the present invention; Fig. 6 is a section taken upon the line 6—6 of Fig. 5, looking in the direction of the arrows; Fig. 7 is a perspective of the novel, nose-rest support shown in Figs. 1 to 6, prior to its assembly with the nose rest; Fig. 8 is a section taken upon the line 8—8 of Fig. 7, looking in the direction of

the arrows; Fig. 9 is a section taken upon the line 9—9 of Fig. 8, looking in the direction of the arrows; Fig. 10 is a section taken upon the line 10—10 of Fig. 5, looking in the direction of the arrows; Fig. 11 is a plan illustrating a step in the manufacture; Fig. 12 is a section taken upon the line 12—12 of Fig. 11, showing the relative position of the parts prior to the descent of the movable die; and Fig. 13 is a similar section, showing the parts in the relative positions occupied after the descent of the movable die.

Each nose rest 10 is composed of some non-metal material, like celluloid, unbacked by any reinforcing or supporting member, such as metal. Each nose rest 10 is provided with an opening 14 extending, in the direction of the thickness dimension of the nose rest, from the inner face of the nose rest, inward a substantial distance toward the outer face 16, as illustrated more particularly in Figs. 6, 10 and 13. The thickness distance between the oppositely disposed faces 16 and 18 is, of course, small compared with the dimensions along said faces in the direction of the length or the width of the nose rest. The metal arm 8 has integral therewith a metal member 20, preferably in the form of a circular disk, that is inserted in the opening 14. The opening 14, into which the metal disk 20 is received, extends over a distance, in a direction along the faces 16 and 18, that is of substantial extent compared with the dimensions of the guard, so as to provide for the use of a substantial amount of metal, which is of corresponding extent. The thickness of the metal disk 20, between the concave and convex faces thereof, is small compared with its diameter, as is shown more particularly in Figs. 4, 6 to 10, 12 and 13, though this metal thickness is very thin compared with the thickness of the nose rest, as is illustrated more particularly in Figs. 4, 6, 10 and 13. The parts are rigidly secured together, as hereinafter described, thus forming an integral, one-piece, unbacked non-metal guard, except for the metal portion 20.

The metal disk 20 is, originally, more or less concavo-convex, or cup shaped, as illustrated more particularly in Figs. 7, 8, 9 and 12, but becomes substantially flattened out, as illustrated in Figs. 6, 10 and 13, during the assembly process of the nose rest 10 with the metal support 8, as hereinafter described. A stem 29 is originally cut out of the metal sheet of which the arm 8 is constituted by slotting at 31, from the periphery 33 of the disk inward to about the center of the disk, and bending the stem 29 out of the plane of the sheet at the convex side, as illustrated in Figs. 7, 8 and 9. Concavo-convex prongs 35 and 37 are thus formed at the sides of the slot 31. It is the thus slotted, pronged disk 20 that is later

embedded in the opening 14 of the unbacked nose rest.

To effect this embedding, the stem 29 is first inserted in a correspondingly shaped-and-sized opening 39 of a fixed die 41, as illustrated in Fig. 12, with the disk 20 exposed and its concave side facing away from the die 41. A strip 43 of the non-metal material is fed through a guide 45 and over the concave side of the disk 21. During its passage through the guide 45, the strip 43 may be very slightly heated in any desired way, preferably electrically, electric terminals for the heater being shown at 47. During a moment of pause in the feed of the strip 43, a movable die 49 is caused to descend upon the strip, from the position illustrated in Fig. 12 to the position illustrated in Fig. 13.

Owing to the above-described relative dimensions of the parts, and the concavo-convex shape of the metal disk 20, as well as the method of manufacture of the disk 20, its periphery 33 is relatively sharp, which sharpness is materially contributed to by the prongs 35 and 37. As the concave side of the disk 20 is disposed adjacent to the under face of the strip 43, as shown in Fig. 12, the sharp portions of the disk 20 are caused to cut their way into this heated, under face of the strip 43 during the application of pressure by the descending die 49. In so doing, the metal disk 20 displaces the non-metal material in this heated under-face area of the metal disk, thus cutting its own opening 14 into the non-metal material, of a size and shape exactly corresponding to the size and shape of the metal disk 20. The metal disk 20 thus becomes securely embedded in the opening 14, in the position formerly occupied by the displaced, non-metal material.

The movable die 49 is provided with a cutting face 51 that, in cooperation with a corresponding face 53 of the fixed die 41, severs from the strip 43, simultaneously with the before-described pressing operation, a portion of the non-metal material that has the shape and size desired for the unbacked, non-metal nose rest 10, as illustrated in Figs. 1 to 6, 10 and 13. The active faces 55 and 57 of the dies 49 and 41, furthermore, are curved, as illustrated in Figs. 12 and 13, to impart the desired, curved shape to the non-metal nose rest 10.

The face 57 of the fixed die 41 has a circular depression 59 into which the non-metal material of the strip 43 is caused to flow or roll over against the convex face of the disk 20, thus locking the disk 20 securely into the opening 14, as is illustrated more particularly at 61 in Figs. 3 to 6, 10 and 13. The pressing force exerted by the moving die 49 is sufficient, not only to press the heated zylonite or other non-metal material into the depression 59, but also to flatten out the concavo-convex disk during the curving of the non-metal nose rest 10, as before described. This flattening out of the metal further acts to embed the metal in under the flowed-over portion 61 of the non-metal material. When the non-metal material becomes chilled, it is almost impossible, without breaking the metal stem 29, to pull the metal disk 20 out of its embedded position. As the relatively large metal disk 20 is forced into the celluloid sidewise, instead of along its edge periphery, a greater holding action is obtained. It requires great pressure to force the disk 20 into the zylonite, and great pressure to remove it. This would be true even if the disk 20 had been un-

slotted at 31, but this slot 31, and the prongs 35, 37 adjacent thereto, contribute to the holding action of the metal in the zylonite.

The described method has been found to eliminate all possibility of the parts becoming separated. The stem 29 is later looped into the openings 6 about the tongue 12, as before described.

Modifications will occur to persons skilled in the art and all such are considered to fall within the spirit and scope of the invention as defined in the appended claims.

What is claimed is:

1. A method of joining a concavo-convex zylonite member to a metal disk having a stem cut therefrom from the periphery of the disk inward, the stem being bent out of the disk at the convex side to provide a slot in the disk, whereby concavo-convex prongs are formed in the disk at the sides of the slot, said method comprising positioning the concave side of the disk adjacent to the zylonite member, heating the zylonite member, pressing the heated zylonite member and the metal disk toward each other along the area of the disk to cause the slotted disk to displace the heated zylonite of the zylonite member throughout the area of the slotted disk to cause the pronged, slotted disk to become flattened and to become embedded in the zylonite member, in flattened form, in the position formerly occupied by the displaced zylonite, and causing the displaced zylonite to flow over the opposite face of the slotted disk.

2. A method of joining an unbacked zylonite nose rest to a substantially flat metal support comprising providing a strip of unbacked zylonite material, positioning the substantially flat metal support flat-wise adjacent to the strip, heating the strip, severing the nose rest from the heated strip and, simultaneously therewith, pressing the heated strip and the metal support flat-wise toward each other along the area of the said substantially flat metal support to cause the substantially flat metal support to become embedded flat-wise in the zylonite nose rest in the position formerly occupied by the displaced zylonite.

3. A method of making a nose guard comprising a zylonite nose rest the thickness of which is small compared with its length or its width and that is supported by a substantially flat metal support the thickness of which is small compared with its length or its width and with the thickness of the zylonite nose rest and the length of which is of substantial extent compared with the length of the zylonite nose rest, the said method comprising positioning a face of the metal support adjacent to a face of a strip of zylonite of the first-named thickness, heating the strip to soften it, severing the nose rest from the heated strip, forcing the metal support flat-wise into the heated zylonite nose rest along the area of the metal support to cause the metal support to displace the heated zylonite of the nose rest throughout the area of the metal support and to cause the metal support to become embedded flat-wise in the zylonite nose rest in the position formerly occupied by the displaced zylonite of the nose rest, causing the displaced zylonite to flow over the edges of the metal support on to the opposite face of the metal support, and permitting the heated zylonite to become chilled to harden it.
